UNITED STATES PATENT OFFICE.

EDUARD HERZIG, OF WEST HOBOKEN, NEW JERSEY.

SHUTTLE.

No. 800,300.

Specification of Letters Patent.

Patented Sept. 26, 1905.

Application filed December 16, 1904. Serial No. 237,061.

To all whom it may concern:

Be it known that I, EDUARD HERZIG, a citizen of the United States, and a resident of West Hoboken, county of Hudson, State of New Jersey, have invented certain new and useful Improvements in Shuttles, of which the following is a specification.

My invention relates to shuttles such as are used in looms, and has for its object to increase the thread-carrying capacity of shuttles of this description and to otherwise improve the construction of such shuttles, as will appear from the detailed description following.

The features of novelty will be pointed out in the appended claims.

Referring to the drawings, which illustrate a specific embodiment of my invention, Figure 1 is a plan view of a loom-shuttle with my improvements applied thereto. Fig. 2 is an enlarged sectional view on the line 2 of Fig. 1, and Fig. 3 is an inverted plan view of a portion of the shuttle.

A is the shuttle-body, which may be of any approved shape and is provided with an opening A'. A plate B is secured to the shuttle-body in such a manner as to form a bottom for said opening, as clearly shown in Fig. 2. An upright hollow support C forms part of or is secured to said plate B and is provided with a projection C' near its upper end. The support C is adapted to carry the spool D, on which is wound the thread E, said spool D being provided with a slot D', which may be of the bayonet type and which co-operates with the projection C' on the support C to prevent the spool D from being accidentally pulled from the support C, it being understood that the spool D does not turn as the thread is used up, said spool being held against turning by the pin-and-slot connection with the support C. Inside of the support C is located a lining C², which is made of wood or any similar substance and is forced into the support C, so as to be practically integral therewith. Into this lining C² is glued or otherwise secured a tube C³, which may be made of porcelain or any other suitable substance which will afford a hard smooth guide-surface for the thread to prevent it from being torn or broken. An arm F, made in such a manner as to have a certain amount of spring, is pivoted at F' upon a projection A² of the shuttle. The screw which forms the pivot F' passes through the projection A² and is provided with a reduced and flattened end F²,

which fits into an angular opening in the plate B. This structure prevents the pivot-screw F' from turning and becoming loose and prevents the arm F from wabbling. The said arm F is arranged to swing on the pivot F' into the position shown by dotted lines in Fig. 1, the free end of said arm F entering a notch F³ in the shuttle-body A, and in this position the arm serves as an additional means for preventing the thread-carrying spool from leaving the support C. When the pivot F' of the arm F is arranged parallel with the spool-support C, as shown, so that the said arm swings in a plane parallel with the end face of said spool, an endwise or axial movement of the spool will have no tendency to swing the said arm F on its pivot into the open position. A material advantage is thus gained over structures in which the pivot of the locking-arm runs at substantially right angles to the spool-support. As the shuttle is used in a loom the thread E will leave the spool, taking the direction indicated by the arrow a in Fig. 1, and will pass down through the tube C³, along the under side of the plate B, and up through an elongated eye G, made from porcelain or other material. From the eye G the thread passes through another porcelain eye H, which is mounted on a cross-bar H', secured to the shuttle-body A, to an eyelet I, mounted or secured to an arm J, pivoted at J' on the cross-bar H'. After leaving the eyelet I the thread passes over to and through an eyelet K', secured to or forming part of another arm K, which is pivoted at K', also on the cross-bar H'. The thread then passes back to and through another eyelet J² on the arm J and then back to and through another eyelet K² on the arm K. After leaving the eyelet K² the said thread is passed through another eyelet J³ on the arm J and then back again to and through an eyelet K³ on the arm K, after which the thread passes through an eyelet L, mounted in a box portion M, it being understood that the portion M forms a container for the arms J and K and their respective eyelets, the said portion M being itself mounted and secured on the shuttle-body A. From the eyelet L the thread passes through two eyelets N and N', secured to the shuttle A, and then through an eyelet O, secured to the end of a spring O', which has its other end fastened in an aperture in the shuttle A. After leaving the eyelet O the thread passes through an eyelet P in the shuttle-body A and then to the point where the said thread is being used.

- The arms J and K are pressed away from each other to bring a tension on the thread by a spring Q, having two members Q' and Q², the said spring Q being coiled around a projection 5 R on an arm R', pivoted to the plate B at R², as shown in Fig. 3. The rivet forming the pivot R² is so tight that the arm R' will be held stationary during the normal operation 10 of the shuttle; but for adjusting purposes the said arm R' may be moved on its pivot R² by means of a suitable tool to increase or lessen the tension of the spring Q on the arms J and K, a slot B' being provided in the plate B for this purpose.
- 15 With the structure I have described it will be seen that the thread-carrying capacity of the shuttle is materially increased and that the thread is subjected to a uniform tension through the medium of the spring-pressed 20 arms J and K and the spring O', and thus prevented from sagging, the resulting work being therefore of a very uniform character. My improved shuttle is also very easily dismantled for any purpose whatsoever, and the spools of 25 thread are also very easily inserted, it being only necessary to mount the thread-carrying spool upon the support C and then thread the shuttle, whereupon it is ready for use.
- Various modifications may be made without 30 departing from the spirit of my invention.
- I claim and desire to secure by Letters Patent—
1. A shuttle comprising a body provided with a recess or chamber, a support extending 35 transversely of the shuttle's path within said recess and secured at one end to a wall of the recess, the other end of the support being free to allow a spool to be slipped thereover, and an arm pivoted at one side of said 40 recess, and mounted to swing across the same about an axis parallel with the said support, so that an endwise or axial movement of the spool will have no tendency to swing the said arm on its pivot.
- 45 2. A shuttle provided with a tension device comprising pivoted arms having thread-guides, springs engaging said arms, and means for moving said springs toward or from the pivot portions of the arms.
- 50 3. A shuttle provided with a tension device comprising a pivoted arm having thread-guides, mating thread-guides arranged opposite the first-named thread-guides, a spring engaging the pivoted arm, and means for moving said spring toward or from the pivot of the arm.
- 55 4. A shuttle provided with a movable ten-
- sion device having thread-guides, a spring for actuating said device and means for moving the spring in its entirety to vary its pressure 60 on said movable device.
5. A shuttle comprising a body provided with a recess or chamber, a support extending transversely of the shuttle's path within said recess, a spool carried by said support, 65 means for locking said spool to the support, a second chamber or recess arranged within the first-named chamber, a movable tension device located in said second-named chamber and provided with thread-guides, and a spring 70 for actuating said device.
6. A shuttle comprising a body provided with a recess or chamber, a support extending transversely of the shuttle's path within said recess, a spool carried by said support, a 75 movable arm adapted to lie near one end face of the spool, said arm being arranged to move in a plane parallel with the end face of the spool, a second chamber or recess arranged within the first-named chamber, a tension device 80 arranged within said second-named chamber and comprising pivoted arms having thread-guides, springs engaging said arms, and means for moving said springs toward or from the pivot portions of the arms. 85
7. A shuttle having a stationary spool-support, a movable resilient arm adapted to lie near one end face of the spool, said arm being arranged to move in a plane parallel with the end face of the spool, and a shuttle-body having a notch into which the free end of said arm is adapted to spring when in its locking position. 90
8. A shuttle comprising a body provided with a recess or chamber, a support extending 95 transversely of the shuttle's path within said recess and secured at one end to a wall of the recess, the other end of the support being free to allow a spool to be slipped thereover, and a resilient arm pivoted at one side 100 of said recess and mounted to swing across the same, about an axis parallel with the said support so that the spool will lie between said arm and the wall to which the support is secured, the body of the shuttle having a notch 105 into which the free end of said arm is adapted to spring when in its locking position.
- In testimony whereof I have hereunto set my hand in the presence of two subscribing witnesses.

EDUARD HERZIG.
